CONTAINER FOR LIQUIDS

Michael Clement Dickins, Bletchley, England, assignor to Twinpak Ltd., Lachine, Quebec, Canada

Filed Sept. 22, 1969, Ser. No. 19,238

Term of patent 14 years

Int. Cl. D9—07

U.S. Cl. D9—175

FIG. 3

FIG. 5

FIG. 1

FIG. 2

FIG. 4

FIG. 1 is an elevational view of a container for liquids showing my new design;

FIG. 2 is an elevational view looking from the right of FIG. 1;

FIG. 3 is a top plan view;

FIG. 4 is a bottom plan view; and

FIG. 5 is a fragmentary sectional view taken on the line 5—5 of FIG. 3.

I claim:

The ornamental design for a container for liquids, as shown.
